UNITED STATES PATENT OFFICE

LIONEL M. WOOLSON, DECEASED, LATE OF DETROIT, MICHIGAN, BY EMMA F. WOOLSON, EXECUTRIX, OF BLOOMFIELD VILLAGE, MICHIGAN, ASSIGNOR TO PACKARD MOTOR CAR COMPANY, OF DETROIT, MICHIGAN, A CORPORATION OF MICHIGAN

INTERNAL COMBUSTION ENGINE

Application filed October 28, 1930. Serial No. 481,757.

This invention relates to internal combustion engines and more particularly to internal combustion engines of the radial cylinder type.

It is a general object of the present invention to provide a novel and improved form of internal combustion engine.

More particularly it is an object of the invention to provide in an internal combustion engine of the radial cylinder type a novel means for operating mechanism for various parts associated with each cylinder.

Another object of the invention consists in providing a sub-assembly for internal combustion engines which contains mechanism for transmitting motion from cams to various moving parts associated with the engine cylinders.

An important feature of the invention resides in the provision of a plate adapted to be fitted in the crankcase of the engine and to have assembled thereon, previous to its positioning in the crankcase, a number of parts whereby a sub-assembly is readily made prior to placing in the engine.

Another important feature of the invention resides in the provision of a sub-assembly for grouping on a partition plate for the crankcase of an engine and containing rocker arms and rock levers for operating valves and fuel injection mechanism.

A further important feature of the invention resides in the provision of an internal combustion engine wherein a large number of parts can be formed upon a plate as a sub-assembly which is later inserted in the engine, eliminating considerable work directly on the engine during assembly or repair.

Other and further features and objects of the invention will be more apparent to those skilled in the art upon a consideration of the accompanying drawings and following specification, wherein is disclosed a single exemplary embodiment of the invention with the understanding, however, that such changes may be made therein as fall within the scope of the appended claims without departing from the spirit of the invention.

In said drawings:

Figure 1 is a radial section taken through

the axis of the crankshaft of an engine constructed according to the present invention and centrally of one of the cylinders;

Figure 2 is a rear elevation of the engine showing the rear cover plate partially broken away and certain parts in section; and

Figure 3 is a face view of the completed sub-assembly.

The present invention deals particularly with internal combustion engines of the so-called radial type wherein a plurality of cylinders, usually an odd number, are radially disposed about a more or less barrel-shaped crankcase with the pistons acting through connecting rods onto a single crank on the crankshaft of the engine. The invention is particularly shown and described in an embodiment of such engine adapted to operate on the Diesel cycle and primarily intended for aviation use.

For a complete disclosure of such an engine reference may be had to my copending application, Serial No. 358,899 for Internal combustion engine, filed April 29, 1929.

Referring now to the drawings for a more complete disclosure of this invention and particularly to Figures 1 and 2 there is shown at 10 a crankcase having a more or less cylindrical portion provided with apertures to receive the reduced inner ends 11 of the cylinders 12 which are held in position by the encircling rings 13 bearing on flanges 14 on the cylinders.

One end of the cylindrical portion of the crankcase is closed by an integral plate 15 provided at 16 with a journal for the crankshaft 17.

The opposite end of the crankcase has an elongated cylindrical portion 20 adapted to be closed at its outer end by means of the end wall or cap 21 shown as somewhat convex. Intermediate this end wall and the portion of the crankcase receiving the crank 22 and connecting rod ends is the partition plate or diaphragm 23 which divides the crankcase into the portion for the movement of the crank and the portion 24 containing operating mechanism for the valves, fuel injectors and the like.

The partition plate 23 is received in a cir-

cular recess 25 in the crankcase and fits against an annular shoulder 26 to which it may be secured by bolts passing through the bossed openings 27 in the partition plate. 5 This partition plate is centrally bored as at 30 to receive the journal 31 for the crank-shaft.

Each cylinder is provided with a valve 32 in the head thereof operated through the 10 rocker arm 33 and push rod 34. The push rod is enclosed in a tubular casing 35 the inner end of which is received in a bushing 36 mounted on a plate 37 which is bolted as at 38 to a flat portion 39 on the periphery 15 of the crankcase portion 20. This bushing 36 passes through the part 20 and forms a guide for the lower end of the push rod.

Extending parallel to and adjacent each casing 35 is a fuel injection pump 40 having 20 a plunger 41 adjustably associated with an actuator rod 42 mounted for reciprocation in a bushing 43 extending through the part 20 of the crank case and being secured to the same plate 37 as is the bushing for the valve 25 push rod.

Journalled for rotation on the portion 50 of the crankshaft to the right of the journal 31, is a sleeve 52 supporting the fuel injection cam 53. Mounted on this sleeve 52 is 50 the hub 54 supporting the valve operating cam 55. The faces of these cams are of about the same radius although, of course, they are provided with different actuating lobes positioned each for its intended purpose. The 55 two cams are adapted to be secured together for rotation in unison by any obvious means such as tight engagement with the sleeve 52 and for the purpose of driving them the valve cam 55 has an overhanging peripheral 40 flange 56 provided on its inner surface with gear teeth 57 which mesh with a pinion 58 suitably supported on a journal and connected to move in unison with the gear 59 which is driven from a pinion 60 on the crankshaft. 45 Thus the two cams are adapted to move in unison and at a speed bearing a definite ratio to the speed of the crankshaft.

In order that the cams may cooperate with the valve push rods and the actuating rods 50 for the fuel injectors intermediate mechanism is necessary and this is carried entirely on the partition plate or diaphragm 23. For this purpose the diaphragm is provided on its outer face with a plurality of hollow studs 55 61 secured therein by pressing or in any other suitable manner and arranged one for each cylinder. Journalled on the cylindrical portions of these studs and adjacent the shoulders thereon which limit their movement into the plate are the hubs 62 of rock levers 63 having thereon followers 64 which bear on the periphery of the fuel injector cam 53.

Journalled on the same studs but separated from the hubs 62 by the separators 65 65 are the hubs 66 of the rocker arms 67 pro-

vided intermediate their ends with rollers 68 journaled on suitable pins 69 and adapted to cooperate with the periphery of the cam 55.

To retain the rock levers and the rocker arms in position on the studs suitable caps 70 70 are fitted over the ends of the studs and held in position by screws threaded into the hollow interior of the studs.

The free end of each rocker arm 67 is cuffed as at 75 to receive the end of a connecting rod 76, the other end of which fits into the bushing 36 to cooperate with the lower end of the push rod therein, whereby the valve may be opened when the roller 68 is lifted by cooperation with a lobe on the 80 valve operating cam.

In order to operate the actuator rod 42 of each fuel injector there is provided a strut 78 having a ball end seated in a cup at the inner end of the actuator rod and with its opposite 85 end being received in a curved channel 79 on the outer surface of the free end of the rock lever for that particular cylinder. In order to vary the stroke of the injector plunger the strut can be moved so that its 90 inner end is closed to or further from the pivot stud for the rock lever and this is effected by means of the adjusting link 80 pivoted at one end to the strut intermediate its ends and pivoted at its other end at 82 to the 95 adjusting ring 83.

This adjusting ring is received in an annular groove 84 in the outer face of the diaphragm plate 23 and is held in position and limited in its movement of rotation by means 100 of the studs 85 fitting through slots 86 in the ring and threaded into the plate 23. Rotation of the ring causes simultaneous and similar movement to be imparted to all of the struts so that the strokes of all of the fuel injectors are adjusted at once. A suitable spring or springs 90 cooperate with lugs 91 on the ring and studs 92 on the partition plate to bias the ring 83 to move the struts toward the far end of the rock levers. Any suitable 110 operating means can be connected to the ring 83 to permit adjustment of the amount of fuel injected to the cylinders and hence the power output of the cylinders.

It will be noted that the diaphragm plate 115 23, although it is perforated, forms, in effect, a partition in the crankcase and that it carries not only the studs 61 but both the rocker arms and rock levers for cooperation with the cams. It likewise carries, by virtue of the 120 adjusting links 80, the struts 78, and the ring 83.

Having all of these parts assembled thereon, prior to its being inserted into the engine crankcase, it greatly simplifies the engine assembly for it permits a large sub-assembly to be made which can be inserted as a unit into the crankcase and bolted into position before the bushings 43 and 36 are inserted and the cams placed on the shaft. Likewise if it is 125 130

desired to make some major repairs on the engine, this sub-assembly can be removed by first removing the cap 21 on the engine and then the plates 37 carrying the bushings and 5 then the cams so that the partition plate can be removed. It should be noted here that the cap 21 carries an integral sleeve 95 for each stud 61, which fits over the cap 70 and ensures a rigid support for the outer end of each stud 10 and likewise prevents it from coming loose from the plate 23.

Having thus described the invention, what is claimed as new and desired to be secured by Letters Patent is:

15 1. In an internal combustion engine, a sub-assembly comprising a crankcase partition plate, valve rockers journaled thereon, fuel injector rockers journaled thereon, fuel injector struts engaging said last mentioned 20 rockers, and means loosely securing said struts to said plate for assembly therewith but permitting motion in respect thereto.

25 2. In an internal combustion engine, a sub-assembly comprising a crankcase partition plate, valve rocker arms journaled thereon, fuel injection rock levers journaled thereon, a fuel injector strut for each of said levers, an adjusting link pivoted to each strut, and means connecting the links to said plate.

30 3. In an internal combustion engine, a sub-assembly comprising, in combination, a crankcase partition plate, studs removably fitted in said plate, rocker arms and rock levers removably journaled on said studs, a fuel injection strut for each rock lever, an adjusting link pivoted to each strut, and means adjustably securing said links to said plate.

35 4. In an internal combustion engine, a sub-assembly comprising, in combination, a crankcase partition ring, studs arranged in a circle on said ring, rocker arms and rock levers journaled on said studs, a fuel injection strut for each rock lever, an adjusting link pivoted to each strut, an adjusting ring concentric to said partition ring and rotatable thereon, and means pivoting one end of each link to said adjusting ring.

40 5. In an internal combustion engine, a barrel-like crankcase having a tubular extension with an open end, a sub-assembly adapted to be bodily inserted into said extension through said open end and comprising a partition plate between the crankcase and extension, studs mounted on said plate and 45 rocker arms journaled on said studs, a cap to close the end of said extension and means on the inside of said cap adapted to slide over and support the end of each stud.

60 6. In an internal combustion engine, a sub-assembly comprising, in combination, a crankcase partition plate, studs arranged on said plate, rock levers journaled on said studs, a fuel injection strut for each rock lever, an adjusting link pivoted to each strut, an adjusting ring rotatable in respect to said plate,

means pivoting one end of each link to said ring and means biasing said ring to maximum adjusted position in one direction.

65 7. In an internal combustion engine, in combination, a crank case of barrel-like form closed at one end, cylinders radiating from said crankcase, a crankshaft journaled in said closed end, a plate removably fitting in said crankcase and providing a second journal for said crankshaft, said plate forming the 70 foundation of a sub-assembly and supporting studs, rocker arms journaled on said studs, valves for said cylinders, means associating said valves and rocker arms and a cam on said crankshaft to cooperate with said 75 rocker arms.

80 8. A sub-assembly for internal combustion engines comprising, in combination, a plate adapted to be secured in the engine crankcase, a plurality of studs mounted therein, a pair of rockers journaled on each stud, means retaining said rockers on said studs, an adjusting ring, means positioning said ring on said plate and limiting the rotary movement thereof, a strut for one rocker arm on each stud, and a link for each strut pivoted thereto and to said ring.

85 9. A sub-assembly for internal combustion engines comprising, in combination, a plate adapted to be secured in the engine crankcase, a plurality of studs mounted therein, a pair of rockers journaled on each stud, means retaining said rockers on said studs, an adjusting ring, means positioning said ring on said plate and limiting the rotary movement thereof, a strut for one rocker arm on each stud, a link for each strut pivoted thereto and to said ring and means between the plate 90 and ring to bias the ring.

100 In testimony whereof, I have hereunto subscribed my name this 24th day of October, 1930.
